BEVERAGE BOTTLE OR THE LIKE

Bryant Edwards, Clarendon Hills, Ill., assignor to Illinois Tool Works Inc., Chicago, Ill.

Continuation-in-part of abandoned design application Ser. No. 247,933, Apr. 26, 1972. This application May 23, 1973, Ser. No. 362,976

Term of patent 14 years

Int. Cl. D9—01

U.S. Cl. D9—100

Fig. 1

Fig. 2

Fig. 3

Fig. 4

FIG. 1 is a side elevational view of a beverage bottle or the like showing my new design;

FIG. 2 is a top plan view;

FIG. 3 is a bottom plan view; and

FIG. 4 is an enlarged fragmentary cross sectional view of the bottom taken on line 4—4 of FIG. 2.

This application is a continuation-in-part of my prior application Ser. No. 247,933, filed Apr. 26, 1972 and now abandoned.

I claim:

The ornamental design for a beverage bottle or the like, as shown and described.
